(57) **CLAIM**

The ornamental design for a bucket, as shown and described.

DESCRIPTION

FIG. 1 is a perspective view of a bucket in accordance with the present invention;

FIG. 2 is a reduced front view of the bucket;

FIG. 3 is a reduced top view thereof; and,

FIG. 4 is a reduced side view thereof.

The broken lines immediately adjacent the shaded areas represent the bounds of the claim and all of the other broken lines are for illustrative purposes only. None of broken lines form a part of the claimed design.

1 Claim, 2 Drawing Sheets

FIG. 1

FIG. 2***FIG. 3******FIG. 4***
